UNITED STATES PATENT OFFICE.

BERNHARD KRÄMER, OF CHARLOTTENBURG, GERMANY, ASSIGNOR TO GENERAL ELECTRIC COMPANY, A CORPORATION OF NEW YORK.

GOVERNING MECHANISM FOR MIXED-PRESSURE TURBINES.

1,013,184.

Specification of Letters Patent.

Patented Jan. 2, 1912.

Application filed April 11, 1911. Serial No. 620,469.

To all whom it may concern:

Be it known that I, BERNHARD KRÄMER, a subject of the Emperor of Germany, residing at Charlottenburg, Germany, have invented certain new and useful Improvements in Governing Mechanism for Mixed-Pressure Turbines, of which the following is a specification.

In the operation of mixed pressure turbines when changing from the low to the high pressure source of supply, a change in the number of revolutions of the turbine shaft takes place. This is particularly objectionable when the turbine is driving an alternating current generator which is connected in parallel with one or more other alternators driven by high pressure turbines or other engines.

The present invention has for its object to decrease the variation in speed of a mixed pressure turbine which takes place in changing over from the low to the high pressure source of supply.

In carrying out my invention the variation in speed of the mixed pressure turbine is reduced by the measure that the exhaust pressure is employed directly or indirectly as a load on the governor, and this in such manner that with a decrease in the pressure of the exhaust steam the speed of the turbine is automatically increased.

In the drawing is shown somewhat diagrammatically, in Figure 1, my invention as applied to a mixed pressure turbine, and Fig. 2 is an end view of such a turbine.

1 indicates a speed governor which is driven directly or through speed-reducing gears by the turbine shaft. The shaft 2 may indicate the main or a secondary shaft of a mixed pressure turbine. The weights of the governor are connected to a sliding collar 3 mounted on the shaft. To the collar is also pivotally secured at 3^a one end of a lever 4. The other end of the lever is pivotally connected at 5 to the rod 5^a that connects the piston 6 of motor 7 with the valve 8 that admits high pressure steam to the turbine. At a point intermediate its ends the lever 4 is pivotally connected to the rod 50 of the balanced pilot valve 9 of the regulator 10. This valve is located within a casting 11 to which fluid from a suitable source is admitted by the conduit 12, the exhaust passing off by the conduit 13. The ports in 55 the casing are connected by conduits 14 and

15 with ports in the motor cylinder, one of said latter ports being above and the other below the piston 6 contained therein.

Situated between the lever 4 and an abutment 16, which may be fixed or hand adjusted, is a coiled compression spring 17 that normally exerts a downward force on the lever and pilot valve 9. Situated in an enlarged portion of the pilot valve casing is a sliding piston or abutment 18 whose movements are responsive to changes in pressure of the low pressure steam. Pressure is communicated by the pipe 19 to the under side of the abutment from the low pressure source of supply. Between the abutment and the pilot valve is a coiled compression spring 20. It will thus be seen that the pilot valve is suspended between two devices which exert their forces in opposite directions. As shown the ports are in what may be termed the neutral position; i. e., the ports controlled by the pilot valve closed and the forces exerted by the upper and lower springs being substantially equal and opposed to each other. The springs are so adjusted or arranged with respect to each other that the lower spring 20 under normal conditions balances the weight of the pilot valve and also the tension of the upper spring 17. The power of the lower spring 20 is varied by the raising and lowering of the abutment 18 in response to changes in pressure of the low pressure source. With a normal exhaust pressure the lever 4, due to the balancing of the opposing forces, will not be loaded but if said pressure falls the tension of the upper spring 17 preponderates. The result of this is to modify the action of the speed governor by applying a force thereto and to the lever 4 in a direction to cause the pilot valve to assume a new position or setting differing from that due to the governor alone which admits fluid to the under side of the motor piston and the latter opens the valve 8. This action it will be seen takes place without any change in speed of the turbine shaft. In other words, the change is due solely to a decrease in pressure of the low pressure source. As soon as the piston starts into motion the pin 3^a on the governor collar becomes the point of fulcrum for the lever 4 and the upward movement of the rod 5^a will restore the pilot valve 9 to its normal position; i. e., where it closes the ports communicating

with the motor 6. In the event of a speed change of the turbine shaft due to load the governor will raise or lower the left-hand end of the lever, the pin 5 acting for the time being as the fulcrum. The rod 5 will restore the pilot valve to its initial position when the movement of the motor piston has satisfied the load requirements by adjusting the valve 8.

10. If the pressure of the low pressure source of steam is now restored to normal, the tension on the lower spring 20 is restored and the position of the pilot valve and tension on the upper spring are also restored.

15. It is not necessary to have the abutment 18 and spring 20 act directly on the pilot valve since the lever 4 may be weighted by applying the force at some other point, but the arrangement shown is the more desirable 20 since the movement of the lever at the point of connection with the stem of the pilot valve is small.

By suitable selection of the pilot valve and of the proportions of the springs the 25 speed of the turbine shaft will be the same regardless of whether the turbine is driven by low pressure steam or high.

In accordance with the provisions of the patent statutes, I have described the principle of operation of my invention, together with the apparatus which I now consider to represent the best embodiment thereof; but I desire to have it understood that the apparatus shown is only illustrative, and that 35 the invention can be carried out by other means.

What I claim as new and desire to secure by Letters Patent of the United States, is,—

40. 1. In a governing mechanism for mixed pressure turbines, the combination of a speed governor, a regulating valve controlled by the governor, means which normally exert opposed and balanced forces on the governor, and a pressure sensitive device which 45 adjusts one of said means thereby disturbing the balance of the forces exerted by said means.

2. In a governing mechanism for mixed

pressure turbines, the combination of a speed 50 governor, a regulating valve controlled by the governor, springs which normally exert opposed and balanced forces on the governor, and a means responsive to a decrease in pressure of the low pressure source of supply of 55 the turbine for changing the force exerted by one of said springs.

3. In a governing mechanism for mixed pressure turbines, the combination of a speed governor, a governor lever, an admission 60 valve, a motor for actuating the valve, a pilot valve for the motor, means exerting opposed and balanced forces on the governor, and a means sensitive to pressure for disturbing the balance of the forces exerted 65 on the governor.

4. In a governing mechanism for mixed pressure turbines, the combination of a speed governor, a regulating valve, a lever attached to the governor and to the rod of the 70 valve, a motor for actuating the valve, a controller for the motor which is connected to the lever, springs acting on the lever in opposition to each other, and a movable abutment for one of the springs which is 75 sensitive to changes in pressure of the low pressure source of supply.

5. In a governing mechanism for mixed pressure turbines, the combination of a speed 80 governor, a regulating valve, a lever attached to the governor and to the rod of the valve, a motor for actuating the valve, a controller for the motor which is attached to the lever, a spring which exerts a force on the lever in one direction, a second spring 85 which exerts a force on the controller in a direction to counterbalance the force exerted by the first on the lever, and an abutment for the second spring which changes its position in response to changes in pressure of the low pressure source.

In witness whereof, I have hereunto set my hand this 20th day of March, 1911.

BERNHARD KRÄMER.
